UNITED STATES PATENT OFFICE.

ARNO F. OTTO, OF MILWAUKEE, WISCONSIN.

SHEET-METAL WINDOW SCREEN.

Application filed June 30, 1926. Serial No. 119,578.

This invention relates to window screens.

Objects of this invention are to provide an all metal window screen of novel construction, which may be readily manufactured in a simple and easy manner, and which is so constructed that it will fit tight in any window, although slight variations in the dimensions of the window may occur.

Further objects of this invention are to provide a novel form of window screen in which a yielding packing is employed in conjunction with, and forming a part of the screen itself, so that the packing will fit against the face of the window casing, and will prevent the formation of cracks which would permit the entrance of insects.

Further objects are to provide a novel form of metal screen so constructed that the channel for the reception of the packing forms a reinforcement or stiffening adjacent the screen margin, and in which such channel cooperates with the retaining member to readily retain the packing in position, in a simple and efficacious manner.

An embodiment of the invention is shown in the accompanying drawings in which:

Figure 1 is an elevation of a window equipped with a screen constructed in accordance with this invention, with parts of the screen casing or marginal portion broken away;

Figure 2 is a transverse sectional view on the line 2—2 of Figure 1;

Figure 3 is a sectional view on the line 3—3 of Figure 1.

Referring to the drawings, it will be seen that a window casing 1 has been disclosed as of the usual construction. This window casing is adapted to receive the screen upon its outer face in distinction to the usual mode of mounting the screen within the casing. By mounting the screen in the manner described, it is possible to use one size of screen for a number of different sized windows which heretofore has been impossible.

Referring to the drawings, it will be seen that the screen is provided with a marginal portion formed of an inner and an outer sheet metal plate 2 and 3 (see Figures 2 and 3) which are integrally joined at their outer ends and receive between them the screen proper or wire mesh member 4. This marginal portion is formed with a channel completely around its marginal portions, as shown most clearly in Figures 2 and 3. The channel is a semi-circle in cross section, as

indicated at 5 in Figure 2 for the side and top marginal portions, and is approximately a quarter circle for the lower marginal portion, as shown at 6 in Figure 3. Within the channel, a packing or gasket is positioned. This packing may be of rope-like formation sufficiently yielding to be readily positioned within the channel and to yield sufficiently to close all gaps between the marginal portions and the window casing. This packing may be, for example, formed of fibrous material, steel wool, rubber, or other suitable material provided it has the characteristics noted above. It is retained in place by means of loops of wire, as indicated at 8, which are passed through apertures formed in the channel portion and extend through the packing, the ends of the wire being twisted together, as shown. Thus an extremely simple retaining means is employed for holding the packing in place.

At the lower portion of the window, the packing 7 bears against the window sill 9, as shown in Figure 3, and completes the tight joint entirely around the screen.

It is to be noted that the wire screen extends between the marginal members and is received in its curved portion. This curved portion, therefore, performs three functions. In the first place, it aids in retaining the wire mesh screen 4, which may, if desired, be spot welded thereto, or riveted, or otherwise secured. In the second place, it increases the strength of the marginal portion against distortion due to its channel shape. In the third place, it forms a channel or pocket for the reception of the packing.

All of these results are attained without an undue increase in the expense of the screen, and also all of these features are highly desirable and permit a novel mode of functioning of the screen, as it completely seals all crevices, and also permits the use of the screen upon different sized windows, as the screen merely contacts with the outer face of the window casing.

Obviously, the screen may be provided with the usual hangers or fittings (see Figure 1), whereby it may be suspended, and with the usual latching means or adjusting means (not shown).

It will be seen that a metal screen has been provided of novel construction, which will effectively seal against the window casing, and which may be employed with a large

number of different sized windows without altering the construction of the window in any manner. Further, it will be seen that the screen may be very cheaply manufactured and may be readily applied.

Although the invention has been described in considerable detail, such description is intended as illustrative rather than limiting as the invention may be variously embodied 10 and as the scope of such invention is to be determined as claimed.

I claim:

1. A window screen adapted to contact with the outer face of a window casing and comprising a mesh member, a border member formed of sheet metal and composed of integrally joined inner and outer strips between which the mesh member is received, said border member being pressed outwardly 20 to form a channel, a packing positioned within said channel, and means for retaining said packing in position.

2. A window screen adapted to contact with the outer face of a window casing and comprising a mesh member, a border member formed of sheet metal and composed of 25

integrally joined inner and outer strips between which the mesh member is received, said border member being pressed outwardly to form a channel, a packing positioned 30 within said channel, and a plurality of wires passing through said channel and through said packing for securing said packing in place.

3. A window screen comprising a mesh member, a border strip formed of two integrally joined plates between which said mesh member is received, said border being outwardly pressed to form a channel extending completely around the screen and having apertures at regular intervals, a packing positioned within said channel, wires passing through said packing and having their ends locked together, whereby said packing is retained in said channel and projects from 40 the face of the screen.

In testimony that I claim the foregoing I have hereunto set my hand at Milwaukee, in the county of Milwaukee and State of Wisconsin.

ARNO F. OTTO.
